UNITED STATES PATENT OFFICE.

LARS JULIUS JENSEN, OF CHICAGO, ILLINOIS.

BRUSH.

Application filed September 2, 1927. Serial No. 217,039.

My invention relates to improvements in brushes, and has for its object the provision of a brush of a construction particularly adapted for the cleaning of receptacles such 5 as cans and similar vessels.

Another object of my invention is to provide a brush that will be particularly adapted to be manufactured on a quantity scale and at the same time to be of a construction adapted 10 to maintain the bristles in their sockets without the possibility of their being pulled loose therefrom.

Other objects and advantages of the method and construction herein employed will appear 15 more fully in the hereinafter specification when taken in connection with the accompanying drawings in which:

Figure 1 is a cross section of the body of my brush, parts being broken away.

Figure 2 is a plan view thereof, partly being broken away.

Referring more particularly to the drawings, 10 is a disk having an interior recess 11 into which the bristles 12 are adapted to enter through the apertures 13,—the bristles being secured in position by vulcanized rubber 14 which fills up the interior of the recess 11. A handle 15 having a flange 15' is provided with an integral threaded portion or 20 plug 16 which is screwed to the base member 10 after being threaded into the socket 17 of a lid 17' which serves to cover the bristle securing vulcanized rubber 14 in the recess 11, the lid being suitably secured to the rubber 25 by bolts accommodated in sockets threaded therein. The flange 15' of the handle 15, as shown in Fig. 1, seats in a shallow recess 19 in the upper surface of the lid 17'.

In the construction of my device the disks 40 10 after being recessed and perforated, which can be performed at practically one operation, are then partially completed by the insertion of the bristles 12 after which the recess is filled up with molten vulcanized rubber. Holes are then bored in the rubber and 45 threads provided for the reception of the screw bolts 18. The lid 17' is next applied and retained securely to the base member 10 by the bolts 18. The threaded end or plug 16 is now inserted into the socket 17 and threaded 50 therethrough into the socket in the base until the flange 15' engages tightly the surface of the upper recess portion of the lid.

The above type of brush has found extensive 55 application in dairies but its field of ap-

plication is quite wide since it affords a ready means of scrubbing and cleaning many of the utensils used for domestic purposes.

While I have shown and described a preferred construction and arrangement of the various parts, it will be understood that my invention is susceptible of many modifications without departing from the essential feature or sacrificing any of the advantages thereof; hence, I do not desire to limit myself to the precise details as set forth but wish to avail myself of such variations and modifications as fairly fall within the scope of the appended claims.

What I claim as my invention, and desire to 70 secure by Letters Patent is:

1. A brush comprising a body, a cap and a handle having a flange, means in said body to receive said handle, said cap adapted to provide a covering for an annular recess in said body, and means in said recess adapted to simultaneously secure bristles mounted in apertures in said body, and to provide means whereby said handle may be additionally secured to said body. 80

2. A brush comprising a handle having a threaded portion and a flange, a brush body having an annular recess and a plurality of perforations on the periphery and bottom of said body adapted to receive bristles communicating with said recess, a bristle securing material within said recess, said bristle securing material being adapted to bind the bristles in position, and means in the brush body to receive the threaded portion and seat 90 the flange of said handle. 85

3. A brush comprising a base member recessed to provide a container for cement, a plurality of bristle accommodating apertures in said base communicating with said container, a central orifice through said base member threaded to accommodate a plug integral with a handle, a lid registering with and fitting over said base in a manner to provide a cover for the cement therein, said lid having a shallow recessed upper surface to provide a seat for a flange on said handle and a threaded orifice in said lid whereby said handle may be screwed through the lid and into the base to hold the cooperating parts 100 of the brush in secure operative contact, substantially as described. 105

In testimony whereof I have signed my name to this specification.

LARS JULIUS JENSEN.
